W. J. SPURR

SCAFFOLD HORSE

Filed Jan. 31, 1925

William J. Spurr.

BY *Spurr Co.*

ATTORNEY

UNITED STATES PATENT OFFICE.

WILLIAM J. SPURR, OF LEONIA, NEW JERSEY.

SCAFFOLD HORSE.

Application filed January 31, 1925. Serial No. 2,102.

To all whom it may concern:

Be it known that I, WILLIAM J. SPURR, a citizen of the United States, and resident of Leonia, Bergen County, New Jersey, have 5 invented certain new and useful Improvements in Scaffold Horses, of which the following is a specification.

This invention relates to scaffold horses and has for its primary object to provide a 10 knock-down and adjustable scaffold horse consisting of relatively few parts of simple form, and which, when assembled, will provide a firm and substantial support for the scaffold platform.

15 It is another object of my invention to provide such an adjustable scaffold horse, which is comparatively light in weight and may be easily and quickly moved from place to place.

20 One of the important features of my present improvements resides in the provision of end supports for a horizontal member of cylindrical form, each of which consists of two diverging legs, having interlocking parts at their upper ends, each provided 25 with means for engagement upon one side of said cylindrical member and adapted to be adjusted circumferentially thereon, together with means for separably clamping said interlocked members to said cylindrical member and thereby maintain the diverging legs 30 in their adjusted positions.

In addition to the means just referred to 35 for adjusting and positioning the diverging supporting legs circumferentially of the horizontal cylindrical member, I also preferably provide an adjustable longitudinal extension for each of said supporting legs, whereby said horizontal member may be 40 vertically adjusted and positioned at any desired height above the ground or floor surface.

It is a further general object of the invention to provide a scaffold horse wherein the 45 several parts may be easily and quickly assembled or disassembled, and which, when not in use, is capable of very compact arrangement, so that the device will occupy but little storage space.

50 With the above and other objects in view, the invention consists in the improved scaffold horse and in the form, construction and relative arrangement of its several parts, as will be hereinafter more fully described, 55 illustrated in the accompanying drawings

and subsequently incorporated in the subjoined claims.

In the drawings wherein I have illustrated one simple and practical embodiment of the invention and in which similar reference characters designate corresponding parts throughout the several views,

60 Figure 1 is a side elevation, illustrating a preferred embodiment of my present improvements,

65 Figure 2 is an end view,

Figure 3 is an enlarged detail vertical section taken on the line 3—3 of Figure 1,

70 Figure 4 is a similar vertical section taken on the line 4—4 of Figure 1,

Figure 5 is a horizontal sectional view taken on the line 5—5 of Figure 4,

75 Figures 6 and 7 are detail elevations of the two interlocking clamping members for the horizontal platform supporting rod, and

Figure 8 is a detail longitudinal section taken on the line 8—8 of Figure 1.

In the accompanying drawing, for purposes of illustration, I have shown a practical embodiment of my present improvements, which I have found very convenient and serviceable in practical use, and in which the horizontal member of the horse upon which the scaffold planks or boards are laid, is in the form of a cylindrical rod 80 5. Preferably, for the sake of lightness, this rod consists of a tube or pipe of any desired length, as required in accordance with the width of the scaffold platform to be arranged thereon.

90 The cylindrical rod 5 is adapted to be mounted or arranged at its opposite ends in suitable supports. As herein shown, each of the supports consists of a pair of legs 6, also preferably of tubular cylindrical form, and of any desired length. One end of each of the supporting legs is fixed in a sleeve 8, formed upon one side of a metal plate 7. If desired, the legs 6 may be removably secured in the respective sleeves 8 by a suitable locking key or pin extending through coinciding openings in the sleeve and leg, or, the leg may be permanently fixed in said sleeve. Each of the plates 7 is provided at one of its ends with a transversely curved flange 9, which is adapted for engagement upon one side of the tubular member 5 as will be more fully hereinafter explained. In spaced relation to the flanges 9, each of the plates 7 is provided upon the inner face 100

105 flange 9, which is adapted for engagement upon one side of the tubular member 5 as will be more fully hereinafter explained. In spaced relation to the flanges 9, each of the plates 7 is provided upon the inner face 110

thereof with a rib, as shown at 10 and 11 respectively. The rib 10 is provided with a lug 12 for interlocking engagement in a complementary recess 13 formed in the rib 11. Between the ribs 10 and 11 and the flanges 9, each plate 7 is provided with an opening therein to receive the connecting bolt 14, said plates being provided at their outer sides with the bosses 15, through which said bolt extends. Upon one end of the bolt 14, a winged nut 16 is threaded to coact with one of the bosses 15 and draw the head 17 on the other end of said bolt into tight engagement with the other boss 15. In this manner, the interlocked plates 7 are detachably connected and the flanges 9 thereof are drawn into tight clamping engagement against the opposite sides of the tubular member 5.

In the lower end of each leg 6, an extension member 18 is slidably fitted, said member preferably having a flange 19 at one end for contact with the floor surface, and being provided with longitudinally spaced openings 20 to register with openings in the wall of the legs 6 and receive a locking pin 21. The member 18 is also preferably of tubular form, and it will be understood that by providing this extensible and adjustable member for each of the legs 6, the length of the supporting legs may be increased or decreased within certain limits to position the platform supporting bar 5 at a desired height above the ground surface.

If desired, for purposes of greater security, the diverging legs 6 may be connected intermediate of their ends, by transverse brace bars 22. However, in many cases, and particularly where the scaffold platform will not be required to sustain very heavy loads, these transverse braces may be dispensed with, so that when the device is not in use, the two legs 6 can be entirely separated from each other.

In the use of the device, as above described, it will be understood that the portions of the plates 7 provided with the curved flanges 9 are relatively yieldable in the adjustment of the clamping nut 16. Thus, normally, the space between the inner surfaces of these flanges is slightly greater than the diameter of the tubular member 5 so that said member may be readily fitted between said curved flanges. After the member 5 has thus been arranged at its opposite ends between the flanges 9 of the spaced supports, the clamping nuts 16 are adjusted so as to draw said flanges 9 inwardly towards each other and thus tightly clamp the same upon the member 5. It will be noted that the upper edges of these flanges are substantially in tangential relation with the periphery of the cylindrical member 5, so that the boards of the scaffold platform may be laid upon the upper side

of the member 5 throughout the length thereof. By loosening the nut 16 slightly, the flanges 9 may be moved circumferentially upon the tubular member 5. By reason of such circumferential adjustment of the supports, at their upper ends upon the scaffold receiving rod or member 5, the lower ends of the supporting legs may be positioned respectively with relation to the ground surface and upon an obstruction, which otherwise could not be avoided, and thus secure a firm and rigid support for the rod 5, which will prevent any tilting of said rod from its proper position to support the scaffold platform in a horizontal plane. In other instances, in addition to this circumferential adjustment of the supports relative to the rod 5, it may be necessary to also use the adjustable extension members 18, whereby one leg can be lengthened relative to the other. It of course will also be apparent that the supports can be readily adjusted longitudinally along the rod 5 and spaced at any desired distance from each other. With a series of such scaffold horses arranged in spaced relation, a scaffold platform of any desired length can be readily erected. A scaffold horse of this construction, as will be apparent from the foregoing description, provides a very firm and rigid support for the platform so that it will not collapse under heavy loads. At the same time, it will be noted that the device is of such construction that it will be comparatively light in weight and can be easily and quickly transported from place to place. This may be done by merely resting the tubular rod 5 at its approximate center upon the shoulder and owing to the fact that the surface of this rod is cylindrical, it will not cut into the shoulder, or cause appreciable discomfort.

From the foregoing description, considered in connection with the accompanying drawings, the construction and manner of use of my improved scaffold horse will be clearly understood. It will be seen that the device, owing to its simple construction may be produced at relatively small cost and by interlocking the supporting legs in each pair with each other, and rigidly clamping the same at their upper ends upon the platform receiving rod, a very rigid supporting structure is produced. When the device is not in use, the clamping nuts 16 can be readily loosened and the cylindrical rod 5 removed. The two supports with this rod can then be very compactly arranged and stored away in a relatively small space.

I have herein illustrated an embodiment of my present improvement, which is very efficient and serviceable in use, but nevertheless it will be understood that the purposes thereof might possibly be attained by other alternative constructions and I therefore re-

serve the privilege of adopting all such legitimate changes in the form, construction and relative arrangement of the several parts as may be fairly embodied within the 5 spirit and scope of the invention as claimed.

I claim:—

1. A scaffold horse comprising a cylindrical scaffold sustaining member, a pair of supporting plates for said member, each 10 plate provided at its upper end with a curved flange adapted to bear against the side of the sustaining member, interlocking means on the lower ends of said plates whereby they interlockingly engage and are 15 disposed in a divergent relation, said plates being apertured between the interlocking means and the flanges and a clamping bolt adapted to extend through said apertures to hold the plates in proper relation to each 20 other and with the flanges against the sustaining member.

2. A scaffold horse which includes a supporting plate, the upper end of which is

provided with a circumferentially curved flange, the lower portion of which, on its 25 inner face is provided with an interlocking rib adapted to interlock with a similar plate, and an apertured boss on the plate intermediate the flange and the rib to receive a clamping bolt.

3. A scaffold horse which includes a pair of supporting plates having their upper ends provided with circumferentially curved flanges and their lower ends provided on the 30 inner faces thereof with interlocking ribs, apertured bosses on the plates between the flanges and the ribs to receive a removable clamping bolt, said bolt adapted when adjusted, to cause the interlocking action of the ribs, and to hold the flanges against the 35 opposite sides of the scaffold sustaining member.

In testimony that I claim the foregoing as my invention, and have signed my name hereto.

WILLIAM J. SPURR.
